US00D780344S

(12) United States Design Patent (10) Patent No.: US D780,344 S
(45) Date of Patent: * Feb. 28, 2017

(54) PORTION OF A SLAB

(71) Applicant: Camibia Company LLC, Eden Prairie, MN (US)

(72) Inventors: Martin E. Davis, Excelsior, MN (US); Jon Louis Grzeskowiak, II, Prior Lake, MN (US); Summer Lane Kath, Eden Prairie, MN (US)

(73) Assignee: Camibia Company LLC, Eden Prairie, MN (US)

() Term: 15 Years

(21) Appl. No.: 29/540,103

(22) Filed: Sep. 21, 2015

(51) LOC (10) Cl. 25-01

(52) U.S. Cl.

USPC D25/149; D5/44

(58) Field of Classification Search

CLAIM

The ornamental design for a portion of a slab, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a top plan view of a portion of a slab, showing our new design.

The depicted surface of the portion of a slab is flat.

1 Claim, 1 Drawing Sheet
